UNITED STATES PATENT OFFICE

2,595,743

SANITARY CLEANING EQUIPMENT

Elton B. Young, Dillsburg, Pa.

Application November 29, 1946, Serial No. 713,059

3 Claims. (Cl. 137—21)

1

My invention relates to cleaning apparatus and more particularly to apparatus for cleaning cesspools, septic tanks, toilets and the like.

The object of my invention is to provide a cleaning apparatus of the class indicated above and adapted to be permanently mounted in a body on the back of a truck chassis.

Another object of my invention is to provide an apparatus of the character indicated above, which can be placed on any convenient place in a street or an alley while operating, and which can be connected with the tank or the like to be cleaned by means of a three inch hose to empty and clean said tank, eliminating all foul odors and the spreading of disease germs by spilling some of the contents removed from the tank or the like.

Other objects of my invention may appear in the following specification describing my invention with reference to the accompanying drawings illustrating a preferred embodiment of my invention.

It is however to be understood, that my invention is not to be limited or restricted to the exact construction and combination of parts described in the specification and shown in the drawings, but that such changes and modifications can be made, which fall within the scope of the claims appended hereto.

In the drawings—

Figure 1 is a sectional view taken on the vertical longitudinal center plane of the cleaning apparatus according to my invention.

Figure 2 is a sectional view taken on line 2—2 in Figure 1, and

Figure 3 is a sectional view taken on line 3—3 in Figure 1.

Referring now in detail to the drawings the cleaning apparatus forming the subject matter of my invention comprises a boiler or tank 10 adapted to be installed or mounted permanently on a truck or the like (not shown).

An opening is arranged in the top of the shell of the tank 10 and is located approximately symmetrically about the intersection of the vertical longitudinal and transverse center planes of the tank. A receiving box 11 is fastened to the top of the tank shell and surrounds the opening therein. A lid or cover 12 is hingedly attached to the upper end of the receiving box 11 and is adapted to close the same.

Adjacent the front end of the tank 10 a power plant 13 is mounted on top of the tank 10 comprising a fly wheel 14 adapted to actuate a pump construction 15. This pump construction has

2

an intake or suction pipe 16 connected to its intake port, which is preferably a three inch pipe, extends rearwardly of the tank 10 and is secured to the outside thereof by one or more clamps 17.

To the outlet port 18 of the pump 15 an angularly bent outlet pipe or conduit 19 is secured extending through the front wall of the receiving box 11 and having its discharge end located 10 inside the opening in the top of the tank 10.

Inside the tank 10, directly under the outlet pipe 19 a partition plate 20 is arranged and fastened to said tank. This partition plate 20 extends part way up in the tank 10 and a baffle plate 21 is pivotally mounted intermediate its ends, above the upper edge of the partition plate 20.

In the lower portion of the partition plate 20 an opening 22 is provided, adapted to be closed 20 by a valve plate 23 slidably mounted on the partition plate 20 and forming valve means. An actuating rod or hand actuatable means 24 is fastened to the valve plate 23, and extends upwardly therefrom into the receiving box 11, where 25 it is slidably mounted in a guide member 25, mounted on a side wall of said box. On its top the actuating rod 24 is provided with a handle 26 to facilitate the manipulation of the valve plate 23.

30 The rear end of the suction pipe 16 is provided with an outer thread 27.

A three inch hose 28, preferably about 200 feet long, is coupled to the suction pipe 16 and the power plant 13 is started, actuating the pump 15.

35 The pivotable baffle plate 21 is arranged, so that it is tilted forwardly and the valve plate 23 is pushed downwardly to close the opening 22 in the partition 20.

40 The free end of the hose 28 is inserted into the cess pool or the like to be cleaned. As long as mostly liquid is removed from the cess pool, the baffle plate 21 remains in the arrangement described above directing the liquid in the for-

45 ward compartment of the tank 10 formed by the partition 20. When the contents of the cess pool being removed therefrom become more solid, the baffle plate 21 is tilted to incline rearwardly by making contact therewith through box 11 50 with a stick or rod held in the hand or by the latter alone to forcibly tilt the baffle plate, so that the solid contents of the cess pool are directed into the rear compartment of the tank 10.

While moving the cleaning apparatus the baffle plate 21 serves as a part of the partition 20 keep-

ing the watery contents in the front tank compartment separated from the heavy sludge collected in the rear tank compartment.

For the process of unloading the cleaning apparatus a discharge outlet 29 is provided in the bottom of the rear tank compartment adjacent the rear end thereof. With this discharge a discharge elbow 30 is connected and a discharge valve 31 is connected with the elbow 30. An unloading hose 32 is adapted to be coupled to the discharge 31.

When the rear tank compartment is emptied as far as possible, the valve plate 23 is pulled up permitting the liquid in the front tank compartment to flow through the rear tank compartment, thereby flushing this compartment clean.

For cleaning toilets having boxes the two tank compartments are filled with clean water. A hose 32 is attached to the outlet valve 31, which is opened to let the water in the rear tank compartment flow into the toilet box. Then the outlet valve 31 is closed, the hose 28 is inserted in the toilet box and the pump 15 is started, sucking the contents out of the toilet box. The baffle plate 21 is arranged to direct the watery toilet contents into the rear tank compartment.

An outlet fixture 33 is provided on the bottom of the front tank compartment, and an outlet pipe 34 is connected therewith and extends rearwardly of the tank, where an outlet valve 35 is connected therewith. A water hose 36 is attached to the water outlet valve 35.

When the watery contents of the toilet box are removed from said box, the water outlet valve 35 is opened and the water hose 36 manipulated to wash the toilet box clean.

In the rear wall of the tank 18 a man hole 37 is provided for cleaning purposes.

Having described my invention I claim as new and desire to secure by Letters Patent:

1. An apparatus for cleaning cesspools and the like comprising a horizontally disposed tank adapted to be mounted on a truck, a pump positioned upon said tank and secured thereto, a power plant disposed adjacent said tank and connected to said pump, an intake port on said pump adapted for connection with a hose, an outlet port on said pump, a vertically disposed partition plate positioned transversely of and within said tank intermediate the ends of the latter and supported on the bottom of said tank, the upper end of said partition plate terminating at a point spaced from the top of said tank, said partition plate dividing the tank into a pair of compartments, a conduit having one end connected to said outlet port and extending through the top of said tank, the other end of said conduit being directly above and spaced from the top of said partition plate, a transversely disposed baffle plate positioned adjacent the upper end of said partition plate and mounted in said tank for swinging movement about a horizontal axis, and valve means in said partition plate and adjacent the lower end thereof and actuatable exteriorly of said tank for controlling the flow of fluid from one compartment to the other.

2. An apparatus for cleaning cesspools and the like comprising a horizontally disposed tank adapted to be mounted on a truck, a pump posi-

tioned upon said tank and secured thereto, a power plant disposed adjacent said tank and connected to said pump, an intake port on said pump adapted for connection with a hose, there being an opening in the top of said tank intermediate the ends thereof, a vertically disposed partition plate positioned transversely of and within said tank intermediate the ends of the latter and supported on the bottom of said tank, the upper end of said partition plate terminating at a point spaced from the top of said tank, said partition plate dividing the tank into a pair of compartments, an outlet port on said pump, a conduit having one end connected to said outlet port and extending through the opening in said tank, the other end of said conduit being directly above and spaced from the top of said partition plate, a transversely disposed baffle plate positioned adjacent the upper end of said partition plate and mounted in said tank for swinging movement about a horizontal axis, valve means in said partition plate adjacent the lower end thereof and actuatable exteriorly of said tank for controlling the flow of fluid from one compartment to the other, and a discharge outlet in the bottom of one of said compartments.

3. An apparatus for cleaning cesspools and the like comprising a horizontally disposed tank adapted to be mounted on a truck, a pump positioned upon said tank and secured thereto, a power plant disposed adjacent said tank and connected to said pump, an intake port on said pump adapted for connection with a hose, an outlet port on said pump, a vertically disposed partition plate positioned transversely of and within said tank intermediate the ends of the latter and supported on the bottom of said tank, the upper end of said partition plate terminating at a point spaced from the top of said tank, said partition plate dividing the tank into a pair of compartments, a conduit having one end connected to said outlet port and extending through the top of said tank, the other end of said conduit being directly above and spaced from the top of said partition plate, said plate being provided with an opening extending therethrough adjacent the lower end thereof, a valve plate positioned for controlling said opening, hand actuatable means connected to said valve plate for actuating the latter, a transversely disposed baffle plate positioned adjacent the upper end of said partition plate and mounted in said tank for swinging movement about a horizontal axis, and a discharge outlet in the bottom of one of said compartments.
